[57] CLAIM

The ornamental design of a resilient foot support, as shown and described.

DESCRIPTION

FIG. 1 is a front top perspective view of a resilient foot support showing my new design;

FIG. 2 is a rear top perspective view thereof;

FIG. 3 is a bottom plan view in an alternate position;

FIG. 4 is a side perspective view in an alternate position;

FIG. 5 is a top plan view of FIG. 2;

FIG. 6 is a front elevational view thereof; and,

FIG. 7 is a rear elevational view thereof.

The broken line showing the human form in FIGS. 3 and 4 is for illustrative purposes only and forms no part of the claimed design.
